(57) **CLAIM**

The ornamental design for a solid state luminaire with dome reflector, as shown and described.

DESCRIPTION

FIG. 1 is a perspective view of the new design for a solid state luminaire with dome reflector for distributing light from solid state light sources such as light emitting diodes; FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The claim is directed to the collective appearance of the components of the solid state luminaire shown. Broken lines are used to show a base that forms no part of the claimed design.
